UNITED STATES PATENT OFFICE.

CHARLES H. TOMLINSON, OF MANSFIELD, OHIO, ASSIGNOR TO THE TOMLINSON COUPLER COMPANY, OF DENVER, COLORADO, A CORPORATION OF SOUTH DAKOTA.

AUTOMATIC CAR AND TRAIN-PIPE COUPLING.

1,094,612.

Specification of Letters Patent. Patented Apr. 28, 1914.

Application filed November 8, 1911. Serial No. 659,083.

To all whom it may concern:

Be it known that I, CHARLES H. TOMLINSON, a citizen of the United States, residing at Mansfield, in the county of Richland and State of Ohio, have invented certain new and useful Improvements in Automatic Car and Train-Pipe Couplings, of which the following is a specification.

My invention relates to car couplings and more particularly to that class designated as automatic car couplings, and one of the chief objects of my invention is to automatically couple the usual air hose connections at the same time that the cars are coupled and to combine both mechanisms in a single body or head.

A further object of the invention is to provide a car coupling which will automatically couple with another of its own kind even though the coupler bodies may be out of line or at different elevations and when coupled will be tightly locked one with the other in order that there may be no appreciable lost motion between the couplings thus locked.

A further object of the invention is to provide a combined device for connecting or coupling both the cars and the air lines, and so dispensing with the risk to life and limb of operators entering between the cars when in coupling either the cars or the air lines, or both.

A further object of the invention is to provide a device of the described character whereby both the cars and the air lines can be uncoupled or disconnected by one operation without making it necessary for a man to enter between cars in uncoupling.

A further object of the invention is to provide a device of the described character in which after the operation of uncoupling the cars and the air lines, the coupler will automatically re-set itself ready for the automatic coupling operation.

A further object of the invention is to provide an automatic coupler for coupling both the cars and the air lines which can be manually coupled to cars fitted with other and common types of couplers.

At the present time practically all railway cars are equipped with air brakes requiring two hose connections to be made for every car coupling, and it is customary for the trainman to go between the cars and couple the cars by hand. Besides the danger to

which the trainman is exposed by going between the cars in making or breaking the hose connections, there is a loss of time, causing considerable delay when a long train is made up.

The present invention, therefore, seeks to provide a suitable and efficient construction which will automatically couple both the cars and the air lines, permit uncoupling by one operation and automatically re-set the coupler ready for again coupling without the necessity for the trainman going between the cars.

The device is so constructed that it is not necessary for the couplers to be in direct alignment when coupling and on curves, yet they are so constructed that when coupled they are locked in order to prevent any appreciable lost motion between them.

My improved coupler may also be manually coupled to other makes of couplers.

These and certain other new and useful objects are accomplished by the invention, the features of novelty of which are fully hereinafter described, in respect to the construction, combination and arrangement of the several parts thereof, the same also being illustrated in the accompanying drawings, forming a part of the specification, and finally more particularly pointed out in the appended claims.

In the said drawings Figure 1 is a plan view of a preferred form showing a single coupler head provided with the improved air connections and coupling mechanism. Fig. 2 is a side elevation of the same, a portion of one of the air hose connections being in section. Fig. 3 is an end view of the head shown in Fig. 1. Fig. 4 is an enlarged detail view in section of the air hose connections. Fig. 5 is a view in side elevation of two coupler heads shown in the operation of coupling in order to illustrate the centering action of the coupling devices. Fig. 6 is a plan view of the coupler shown in Fig. 5.

Referring now to the drawing illustrating one exemplification of the invention, the coupler head or housing of somewhat unusual form consists of a hollowed casting designated by the reference character 10, and is provided with a flanged face 10^a. The coupling devices, of which there is one in each coupler head, are designated by the reference character 12, and are provided with a hook shaped forward extremity 11^a.

adapted to engage with the corresponding portion of a similar hook shaped coupling device on another coupler head. The hook shaped coupling device 12 is provided with a rearwardly extending shank, the extreme rearward end of which within the housing of the coupler head is pivotally connected thereto by pin 13 passing through the housing. A flat spring 14 is secured in the housing preferably by pin, as indicated at 15. This spring is preferably supported for a portion of its length adjacent the pin 15 by the wall of the housing, and has its free end in engagement with the pivoted coupling device 12, and normally tends to force the hook portion of the coupling device 12 toward the center or axial line of the housing. The coupler head or housing 10, it will be understood, forms the forward extremity of a pivoted draw-bar connected with the car at its rear extremity in a manner that is common and will be readily understood by reference to my prior U. S. Patent No. 814,924, granted March 13th, 1906, of which the present invention is an improvement. The coupling device 12 is permitted to move within the limits of the housing on pivot pin 13 under the control of flat spring 14 and cam 17 pivoted in the housing on pin 18 under the control of the cam lever 16, which latter is fixed to cam 17 within the housing and extends to the exterior of the coupler head through the slot 10^a in the wall thereof. The lever 16 is provided with suitable means for operating it, as for example, the chain 29. Although a chain 29 is illustrated, it is evident that any suitable flexible device may be employed for this purpose, and may be extended to enable the operator to grasp the same without entering between the cars. The cam 17 is provided with two cam arms 19-20, the former of which is adapted to contact with a rolling action on the shank of the coupling device 12 within its own housing to operate the coupling device 12 on its pivot pin 13 away from the center or axial line of the coupler head and against the action of the flat spring 14. The cam arm 20 on cam 17 is formed to press on the beveled point of the hooked coupling device of the companion coupler when in the coupled position.

The flange face 10^a of the coupler head or housing is adapted to coöperate with the similar part of a companion coupler when in the coupled position, and in order to facilitate the coupling devices in holding the companion couplers together pins 21, of which there are preferably two or more, are beveled or pointed and secured to the face of the flange 10^a, being adapted to enter corresponding counter-sunk holes 22 of the companion coupler.

Two air connections are shown, being placed in a vertical plane on the center line

of the coupler. The details of construction of these connections are shown in the enlarged section view in Fig. 4, and in the sectional portion of Fig. 2. On the upper and lower sides of the coupling head or housing 10 in the central vertical plane are housings indicated by the reference character 28, which opens both to front and rear, opening to the front through the flanged face 10^a and opening at the rear to permit the rearwardly extending threaded end of sleeve 24 to pass through the housing and receive the internally threaded forward end of the elbow 26, which is adapted to be connected with train pipes 40, of which, as stated, there are two. An air tight joint between elbow 26 and sleeve 24 is secured by reason of the interposed gasket 27. Sleeve 24 is slidably mounted within the housing 28 and through the opening at the rear thereof, and is provided with an enlargement at its forward extremity which is substantially flush with the flanged face 10^a and provided on its interior with an annular groove adapted to furnish a seat for the circular air pipe gasket of rubber or other suitable material which is indicated by the reference character 23.

A spring, indicated by the reference character 25, surrounds the sleeve 24 on the interior 32 of the housing 28, and is seated at one end on the enlarged end of the sleeve 30, and at the other end against the rear wall of the housing 28. This spring, by normally exerting its action between the wall of the housing and the enlarged end of sleeve 30, holds the forward end of the elbow 26 against the outside wall of the housing 28, and when in this position the front face of the gasket 23 projects beyond the face of the flange 10^a of the coupler head or housing. The spring 25 is given sufficient compression to force the sleeve and the gasket thereon outwardly to cause it to make an air-tight joint with another gasket on a companion coupler brought into contact with it.

The center opening of the coupler head is flared outwardly or toward the companion coupling device with which it is adapted to coöperate on both the upper and lower sides of the opening at the side of the opening opposite the normal position of the coupling device within the housing, such flared portions being indicated by the reference character 33, such construction being adapted to assist the coupling device of a companion coupler head to enter when the coupler heads are not in alinement. A hole extending vertically through both the upper and the lower walls of the housing of the coupler head opposite the flared portions 33 is indicated at 36, the same being adapted to receive a coupler pin of the ordinary form when coupling with a coupler of another design, as, for example, with a car fitted

with the ordinary coupler bar or link provided with holes near the ends thereof.

The operation of the device is as follows: When two couplers are brought together 5 the points of the coupling devices 12, indicated by the reference character 12^a, will each enter the enlarged beveled opening 33 in the housing of the opposite coupler head, and when they have entered to about the 10 distance shown in dotted lines in Figs. 5 and 6, the coupler heads will be forced into approximate alinement due to the fact that the top and bottom of the coupling devices extending backward from the points 12^a are 15 parallel, and as soon as the parallel portion enters the housing the contact with the beveled top and bottom sides 33 of the opening in the heads will partially aline them and limit vertical movement of the heads with 20 respect to each other. The beveled coöperating faces of the coupling devices 12 are indicated by the reference character 12^b and terminate in surfaces 12^c approximately parallel with the axial line of the couplers and 25 the horizontal alinement of the coupler heads is obtained when the beveled faces 12^b slide past each other until the faces 12^c on each of the coupling devices register, forcing the coupling devices outwardly against 30 the pressure of the springs 14. At this stage in the coupling operation the coupling devices will remain stationary with respect to lateral movement in the housings in each of their respective coupler heads until the surfaces 12^c shall have moved past each other 35 when the coupling devices, under the action of their respective springs 14, will engage each other. When the coupler heads have approached each other to the point where 40 the parallel surfaces 12^c on the coupling devices are in engagement, the beveled points of the pins 21 will be in position to enter the holes 22 which have been brought into approximate alinement by the beveled coupling devices. As the coupler heads move toward each other and just before the flanges 45 12^a come into contact, the air connection gaskets 23 will be forced together and pressed back into the housing 28 against the action of springs 25. When the flanges 10^a have been 50 brought into contact the coupling devices 12 will become interlocked, due to the pressure of the springs 14, which will lock the couplers together. Air pressure may now be turned into the line.

It will be seen that the functions of pins 21 and their coöperating recesses in the companion coupler head is to finally aline both vertically and laterally the coupler heads 55 just before the air base gaskets come in contact with each other and prevent any relative vertical or lateral movement of the gaskets in relation to each other, and the interlocking of the coupling devices 12 prevents longitudinal movement between the cou-

plers. The necessity of such means to effectively prevent vertical and lateral movement between the coöperating gaskets on joined couplers will be apparent from the fact that train pipes carry air under high pressure which must be maintained constant under control since any reduction in the pressure in the train pipe, on automatic air brake systems in common use will set the 70 brakes.

In uncoupling it is necessary to pull chain 29 on one coupler only, which may be arranged conveniently accessible at any point from between the cars. The rocking of the lever 16 on axial pin 18 will rock the cam 17, which will force the coupling devices 12 apart against the action of springs 14 and render the couplers free to separate and open the air connection. When the couplers are thus uncoupled and the pull of the chain 29 released, springs 14 return the coupling devices 12, cam 17 and lever 16 to their normal uncoupled positions, and the couplers are reset automatically and ready 75 to be coupled.

When it is desired or necessary to couple with other makes of couplers, the coupling devices 12 may be pulled to one side to permit the other coupler to come in contact with the face 10^a and a coupler bar or link 80 having a pin hole near the end may be inserted within the housing 10 and a coupling pin dropped through the registering holes 85 36 of the housing and the hole in the coupling bar or link.

While I have shown the details of the preferred embodiment of the invention, it is apparent that various modifications may be made in the construction, combination and arrangement of the several parts by those skilled in the art without departing from the spirit and scope of my invention, and it is not desired to be limited to the exact details shown.

I claim:

1. In a car coupler the combination with companion coupler heads, of coupling devices on said heads, means on said coupling devices for interlocking said devices in coupling relation, means on the coöperating faces of the coupler heads independent of said coupling devices for interlocking said coupler heads to prevent relative vertical and lateral movement when coupled and just prior to the interlocking of said coupling devices in the coupling relation, and fluid connections having terminals in the coöperating faces of the said coupler heads, said connections being adapted to form fluid tight joints with each other.

2. In car and train pipe couplers, the combination with coupler heads having interlocking coupling devices projecting from the adjacent faces thereof, of coöperating projections and intersections on the said ad-

- jacent faces, the said coupling devices being adapted to guide the said projections and intersections into engagement, and the said projections and intersections being adapted 5 to aline the said coupler heads before the adjacent faces meet, and fluid connections on the coupler heads adapted to form a fluid tight joint when coupled.
3. In car and train pipe couplers, the combination of coupler heads having counterpart projections and intersections on the adjacent faces thereof to prevent relative vertical and lateral movement, projecting interlocking coupling devices to prevent longitudinal movement and aline the coupler heads before the adjacent faces meet and before the said counterpart projections and intersections coöperate, and an air connection on each coupler head adapted to form 10 an air-tight joint with a similar air connection on its companion coupler head.
4. In car and train pipe couplers, the combination of coupler heads having counterpart projections and intersections on the adjacent faces thereof to prevent relative vertical and lateral movement, projecting interlocking coupling devices to prevent longitudinal movement, coöperating means on 15 the coupling devices and the coupler heads for partially alining the coupler heads before the adjacent faces meet and before the said counterpart projections and intersections coöperate, and an air connection on each coupler head adapted to form an air-tight joint with a similar air connection on its companion coupler head.
5. In a car coupler, the combination with a coupler head provided with an air connection, of a coupling device carried thereby adapted to coöperate with a similar coupling device on a companion coupler head also provided with an air connection, means 20 independent of said coupling device for interlocking the said coupler heads against vertical and lateral movement, said means comprising a pin projecting from the forward faces of each of said coupler heads and

adapted to register with an opening on each of the companion coupler heads, said pins having points at their extremities and being 50 cylindrical for a portion of their length and adapted to aline the said coupler heads prior to the contact of the air connections and to lock said heads with respect to relative lateral and vertical movement during the contact of the air connections. 55

6. In car and train pipe couplers, the combination of hollow coupler heads having counterpart projections and intersections on the adjacent faces thereof to prevent relative vertical and lateral movement, projecting interlocking coupling devices to prevent longitudinal movement, and aline the coupler heads before the adjacent faces meet and before the said counterpart projections 60 and intersections coöperate, and an air connection on each coupler head adapted to form an air tight joint with a similar air connection on its companion coupler head.

7. In a car coupler, the combination with 70 coupler heads each provided with an air connection, of coupling devices in each of said heads adapted to coöperate for interlocking the coupler heads against relative longitudinal movement when in coupling 75 relation, means independent of said coupling devices comprising cylindrical pins having conical forward extremities, one to each head, projecting from the forward face of each of said coupler heads and being 80 adapted to register with an opening on the forward face of its coöperating head, and interlock said heads with respect to relative vertical and lateral movement during 85 the contact of the air connections.

In testimony whereof I have signed my name to this specification, in the presence of two subscribing witnesses, on this 6th day of November A. D. 1911.

CHARLES H. TOMLINSON.
